TOOL FOR APPLYING CABLE CLIPS

Bernard V. Kruger, Long Beach, Calif.

Application May 31, 1943, Serial No. 489,173

3 Claims. (Cl. 218—19)

This invention has to do with a tool for applying devices known as cable clips, it being a general object of the invention to provide a simple, effective and practical device or tool for applying a cable clip to a wall fixture, junction box, or other part to which such clip is applicable.

There are various situations in which cables, or the like, are joined with other parts such as fixtures, junction boxes, or panels. Devices known as cable clips are commonly employed in making such connections. In using such cable clips it is common to form a hole or bore through the wall to which the clip is to be applied. The clip itself is a sheet metal member having ears to engage the inner and outer surfaces of the wall surrounding the opening therein. The clips as provided have pre-formed radially projecting ears at what I will term their inner ends to engage the inner surface of the wall, and axially projecting ears at their outer ends designed to be bent over or outward to engage the outer surface of the wall. Cable-engaging arms also project from the outer ends of the clips. In practice the clips are applied by merely bending the outer ears over. However, that operation, though seemingly simple, actually gives considerable difficulty. In most cases it is attempted by means of hammering, and as a result it is not infrequent that the wall to which the clip is applied is marred or injured. Further, in practice, it is extremely difficult to get the ears tight against the surfaces so that the clip is firm in the opening.

It is a general object of this invention to provide a tool for applying clips which operates to simply, quickly and effectively bend the ears of the clips in a manner to accurately and closely conform to the surfaces of the clip-holding wall.

It is another object of my invention to provide a device of the general character mentioned which effectively bends the ears of the clips without hammering action or without in any way injuring or damaging either the clips or the parts to which they are applied.

Another object of my invention is to provide a tool of the character mentioned which is extremely simple of construction and also simple and convenient to handle, making it possible to use in confined places and where it is difficult to work.

The various objects and features of my invention will be fully understood from the following detailed description of a typical preferred form and application of my invention, throughout

which description reference is made to the accompanying drawing, in which:

Fig. 1 is a front end elevation of a clip of the type handled by the tool of the present invention. Fig. 2 is a side elevation of the clip showing it inserted in an opening provided in a wall and in position ready to be secured in the opening. Fig. 3 is a view illustrating a fixture or junction box having a clip applied thereto and ready to receive a cable, or the like. Fig. 4 is a side elevation of the tool provided by my invention. Fig. 5 is an enlarged longitudinal detailed sectional view of the tool showing it in working relation to a clip and wall, the parts being shown in section and in starting position, and Fig. 6 is a detailed transverse sectional view taken as indicated by lines 6—6 on Fig. 5.

The tool of the present invention is applicable to clips of various styles, sizes or designs. However, it is particularly applicable to the standard type of clip commonly used to join cables with devices such as junction boxes, panels, etc.

In Fig. 3 I illustrate a side elevation of a typical fixture or junction box 10, the side wall 11 of which is cylindrical. The wall 11 has an opening to which a clip 12 is applied. Fig. 2 illustrates the curvature or contour of the wall 11 at the point where the clip is applied, the clip being shown inserted in an opening 13 formed in the wall 11 for that purpose. The clip illustrated includes, generally, a split ring-shaped body 14 provided at what I will term its inner end with a plurality of radially projecting ears 15 and at its outer end with a plurality of axially projecting ears 16 and a plurality of axially projecting cable clamping arms 17. There are, in effect, three inner ears 15 spaced 120° apart around the body, one of these ears occurring at the split 18 in the body so that it is divided, having one portion at either end of the body. There are, in effect, three cable clamping arms 17 located at the outer end of the body opposite the inner ears 15, the arm occurring at the split 18 being divided as shown in Figs. 1 and 2. There are three outer ears 16 and they are spaced between the cable clamping arms 17. With this general arrangement the inner ears and outer ears are not opposite each other at the two ends of the body 14, but are spaced substantially 60° apart around the body.

The tool provided by my invention includes, generally, two cooperating die members A and B. The die member A engages or cooperates with the inner end portion of the clip while the die member

B engages or acts on the outer end of the clip. The invention provides means C for operating the die members A and B so that they act to turn the outer ears 16 outwardly to clamp them tightly against the outer surface 20 of the wall 11.

The inner die member A has a body portion 21 provided with a central or axial threaded opening 22 to receive the operating screw 23 of the means C. The invention provides a hub 24 on the inner or working end of the die member A to fit into the inner end portion of the clip body 14 as clearly shown in Fig. 5. The invention further provides an ear engaging face 26 on the inner end of the die member body surrounding or projecting beyond the hub 24 and having a curvature or contour corresponding to that of the inner surface 27 of the wall 11. The ear engaging face 26 is designed to bear against the inner ears 15 of the clip as the tool operates and to shape or form the inner ears to the contour of the inner surface 27 of the wall 11. The clips as provided may have the inner ears 15 projecting radially, as shown in Fig. 2, in which case the ear engaging face 26 of the die member A operates to shape or conform the inner ears so that they bear tightly against the inner surface 27 or take the contour thereof.

The outer die member B is designed to deflect or bend the outer ears 16 of the clip outwardly into bearing engagement with the outer surface 20 of the wall 11. The die member B has a body portion 30 provided at its inner end with a hub 31 similar to the hub 24 of die member A and designed to enter or fit into the outer end portion of the clip body 14. A clip-forming face 33 is provided on the inner end of the die member B surrounding or projecting outwardly from the hub 31, the face 33 being shaped to correspond to the curvature or contour of the surface 21 of the wall 11 so that it acts to give the outer ears 16 that shape or contour. A curved portion or fillet 34 joins the hub 31 and the ear forming surface 33 and acts to start the ears outwardly as the tool is operated. This fillet is best shown in Fig. 5 of the drawing.

It is important that the tool be such as to effectively bend or act on the ears of the clip without distorting or in any way disturbing the clamp arms 17 thereof. To accomplish this I provide longitudinal channels 36 in the body 30 of die member B to freely receive or pass the arms 17. There being in general three clamp arms 17 I provide three channels 36. These channels allow the die members A and B to be moved axially relative to each other without in any way disturbing or distorting the clamp arms.

The means C provided for operating the die members A and B includes, primarily, an operating screw threaded into the opening 21 in die member A and slidably fitting a bore or opening 40 formed axially in the body 30 of die member B. A hex head, or the like, 41 is provided on the outer end of the screw 23 to engage the outer end face 42 of the die member.

As the tool illustrated is operated it is important that it be in the correct rotative position in the opening 13 so that the ear engaging faces of the die members are concentric with the axis of curvature of the wall 11. For this purpose I provide a handle 45 on the die member B preferably projecting radially therefrom in a manner to be conveniently engaged by the operator. The handle 45 may be a bar threaded into an opening provided in member A.

In using the tool the clip, as shown in Figs. 1

20 and 2, is first inserted in the opening 13 provided in the wall 11 so that the inner ears 15 of the clip contact the inner surface 27 of the wall. The die members A and B of the tool are then applied to or assembled in engagement with the clip by applying die member A to the inner end, die member B to the outer end of the clip, and operating the screw 23 to bring the parts to the position shown in Fig. 5. From this starting position as the screw 23 is operated and the handle 45 held to maintain the inner die member in the proper rotative position relative to the wall 11 the die members are moved or forced together so that the outer die member B moves toward the wall 11 and in so doing first deflects the ears 16 outwardly into engagement with the face 33 of die member B. As the operation continues and the die member B approaches the die member A the outer ears 16 are bent to conform to the outer surface 20 of wall 11 and as the final pressure is applied the inner ears 15 and the outer ears 16 of the clip are simultaneously and effectively forced into gripping engagement with the surfaces of the wall 11. This operation having been completed the screw 23 is operated to disengage the die members allowing them to be taken from the clip. By the operation of the tool as above described the ears of the clip are tightly applied to the surfaces of the wall 11, this having been accomplished without in any way impairing the wall 11.

It is to be understood that if the invention is to be used in applying clips to walls shaped differently from what I have shown the parts of the tool may be shaped to bend the ears to fit or conform to such shapes.

Having described only a typical preferred form and application of my invention, I do not wish to be limited or restricted to the specific details herein set forth, but wish to reserve to myself any variations or modifications that may appear to those skilled in the art or fall within the scope of the following claims.

Having described my invention, I claim:

1. A tool for applying a clip to a curved wall, the clip including an annular body to be inserted in an opening in the wall and having inner ears radially projecting to engage the inner surface of the wall, outer ears projecting axially from the outer end of the body and adapted to be bent into engagement with the outer surface of the wall, and clamp arms projecting from the outer end of the body, the tool including, an inner die having a hub to enter the annular body and a die face surrounding the hub to engage the inner ears and curved to correspond to the inner surface of the wall, an outer die having a hub to enter the body, a die face surrounding the hub to engage the outer ears and bend them into engagement with the outer surface of the wall and being curved to correspond to the outer surface of the wall, the outer die having channels to freely receive the arms, a screw carried by the outer die having a head at the outer end of the outer die and threaded into the inner die, and a handle on the inner die.

2. A tool for applying a clip to a wall, the clip including an annular body to be inserted in an opening in the wall and having inner ears radially projecting to engage the inner surface of the wall, outer ears projecting axially from the outer end of the body and adapted to be bent into engagement with the outer surface of the wall, and clamp arms projecting from the outer end of the body, the tool including an inner die having a

hub to enter the annular body and a die face surrounding the hub to engage the inner ears, an outer die having a hub to enter the body, a die face surrounding the hub to engage the outer ears and bend them into engagement with the outer surface of the wall, the outer die having channels to freely receive the arms, and means interconnecting said dies for causing axial compressing movement thereof.

3. A tool for applying a clip to a curved wall, the clip including an annular body to be inserted in an opening in the wall and having inner ears radially projecting to engage the inner surface of the wall, outer ears projecting axially from the outer end of the body and adapted to 15 be bent into engagement with the outer surface

of the wall, and clamp arms projecting from the outer end of the body, the tool including an inner die having a hub to enter the annular body and a die face surrounding the hub to engage 5 the inner ears and curved to correspond to the inner surface of the wall, an outer die having a hub to enter the body, a die face surrounding the hub to engage the outer ears and bend them into engagement with the outer surface of the wall and being curved to correspond to the outer surface of the wall, the outer die having channels 10 to freely receive the arms, and means interconnecting said dies for causing axial compressing movement thereof.

BERNARD V. KRUGER.
